CLAIM

The ornamental design for a simulated electronic alarm, as shown and described.

DESCRIPTION

FIG. 1 is a perspective view of a simulated electronic alarm showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof, the left side being substantially a mirror image of the right side.

FIG.1

FIG.2
